UNITED STATES PATENT OFFICE.

DUNCAN L. McCORKINDALE, OF HOLYOKE, MASSACHUSETTS.

WINDOW-FASTENER.

1,101,867.

Specification of Letters Patent.

Patented June 30, 1914.

Application filed September 1, 1910. Serial No. 579,967.

To all whom it may concern:

Be it known that I, DUNCAN L. McCORKINDALE, a citizen of the United States of America, residing at Holyoke, in the county of Hampden and State of Massachusetts, have invented a new and useful Window-Fastener, of which the following is a specification.

My invention relates to improvements in automatic or semiautomatic locking devices for windows, and consists essentially of a member of certain peculiar construction having a cam-locking surface and one or more dead-locking points, such member being designed to be pivotally attached to one side of a window casing, as hereinafter more fully set forth.

The object of my invention is to provide an inexpensive safety catch for windows, which, though simple in construction and operation and easily and quickly applied, is, nevertheless, strong and durable and capable of locking a window sash at practically any point of elevation, and of holding it against anything less than a force sufficient to break and destroy some of the surrounding or adjacent parts. It is practically impossible to open a window, secured with this device, from the outside, without, as 30 already intimated, actually breaking some part or parts.

A further object is to provide a cam fastener with at least one and for the lower sash usually two dead-locks which will be brought into operation in the event the cam-lock fails to hold, as when the window fits loosely in the casing and is forced by said cam-lock, the dead locks on the fastener having two coming into action sequentially. 40 I attain these objects by the means illustrated in the accompanying drawings, in which—

Figure 1 is a perspective view of a window fastener which embodies my invention in a practical form, such fastener being for a lower sash; Fig. 2, a front side elevation of said fastener, showing it applied to a window casing and in operative relation to the lower window sash; Fig. 3, a similar view, showing the first dead-lock in engagement with said sash; Fig. 4, still another similar view, showing the second dead-lock in action, and, Fig. 5, a front side elevation

of a fastener suitable for an upper window sash.

Similar figures refer to similar parts throughout the several views.

In Figs. 2, 3 and 4, a fragment of the left-hand side of a window casing appears at 1, and a fragment of the abutting side of a lower window sash at 2. At 3 is represented the glass, in section, in the sash 2. Either form of the fastener comprises a head 4 having a peripheral cam-locking surface or cam-lock 5, the face of such surface being widened by means of a flange 6 on the front side of said head and coinciding peripherally with the corresponding edge of said head, and a dead-locking point or dead-lock 7 produced by giving more or less of a sharp edge to said cam-lock at one end, and preferably reversing the curve slightly adjacent to said dead-lock.

In addition to the elements mentioned above, the lower sash-fastener has a tail-piece 8 which is provided with a dead-locking point or dead-lock 9 at its outer end, formed by beveling such end to give more or less of a sharp edge to this part, said dead-lock being coincident with the inner edge of 80 said tail-piece. The dead-locks 7 and 9 are parallel with the axis of the fastener, represented here by a screw 10 which passes through an opening 11, Fig. 1, in the head 4, to secure said fastener to the casing 1 85 and upon which said fastener is free to swing. The transverse direction of the cam-lock 5 at all points is also parallel with the aforesaid axis. As here shown, the head 4 has a beak-like configuration at one end, and the dead-lock 7 forms the outer terminal of 90 this portion of said head. By preference, the fastener is so constructed that an acute angle would be formed by two lines extending from the two dead-locks to the axial center of said fastener, since the proper operation of said dead-locks, or the actuation into engagement with the sash of the dead-lock 9 by the dead-lock 7, when the latter fails to hold, is thus insured.

Owing to the fact that, for an upper sash, the fastener must bridge the space above the lower sash, I provide the fastener for such upper sash with a longer tail-piece, as shown at 12, in Fig. 5, and locate the opening for 105 the screw or other pivotal member far

enough from the head 4 in said tail-piece to enable said member to be inserted in the side of the casing as before. The opening just referred to appears at 13. Necessarily, the 5 second dead-lock is omitted from this fastener, and it might be, of course, from the other. Either fastener is preferably hung on the pivot or screw 10 so that the "low" part of the cam-lock 5 contacts with the sash 10 2—see Fig. 2.

Owing to the shape of the head 4, and more especially to the shape of the cam edge of the same, the bottom sash can be lowered or the top sash raised freely and 15 without interference on the part of the fastener, unless said fastener be tightly engaged therewith in the manner described below, but when either sash is moved in the opposite direction, that is, in the direction to 20 open it, the tendency of said fastener is to automatically lock the sash, by reason of the fact that said fastener is then rocked on its pivot 10 in such a way that its cam-lock 5 binds on said sash and crowds it so hard 25 against the parting strip (not shown), in the case of the lower sash, or against the outer side (not shown) of the groove or channel 16, Figs. 3 and 4, in the casing for the windows, in the case of the upper sash, 30 that the frictional resistance resulting from the engagement between the parts thus produced cannot be overcome. The action of the cam-lock which produces this binding effect will be readily understood. It is 35 usually necessary, therefore, in opening the window to hold the fastener in such a way that the low part of the cam-lock 5 is presented to the sash. To facilitate this latter 40 operation on the part of the upper-sash fastener, a cord 14 may be attached to the free end of the tail-piece 12. Thus by drawing the cord 14 downward the fastener will be rocked on its pivot to throw its cam-lock out of contact with the sash. A pin, as 15, may 45 be located in the casing, above the upper-sash fastener, at a point where it will be struck by said fastener, when the latter is operated by the cord, before the fastener arrives at the dead-center. Without this pin 50 the associated fastener would frequently be thrown over into an inoperative position.

As a rule, after the window has been opened to the desired extent, or when it is to be locked in its closed position, the tail-piece 8 or 12 is grasped and swung or turned 55 in the proper direction to force the cam-lock 5 hard against the sash 2. The window is now securely locked, and even to close the same it will be necessary frequently first to 60 loosen the fastener through the medium of its tail-piece. For a window which fits the casing with ordinary snugness, the cam-lock 5 is all that is required to lock such window, and the greater the force exerted on said 65 window, in the direction to open it and con-

sequently to rock the fastener so that the latter presents still "higher" parts of the cam, the greater the resistance offered by said fastener in conjunction with the other frictionally-engaging parts. In the event, 70 however, that the cam-lock 5 fails to hold the window, a possible contingency due to soft wood, a loose fit, or other causes, some or all, then the motion imparted to the fastener, by the action of the sash on said cam-lock, brings the dead-lock 7 into play, as in Fig. 3. Seldom will the dead-lock 7 fail to hold, but for any possible contingency that might arise, wherein the lower-sash fastener is concerned, the dead-lock 9 is present to 80 meet it; hence, if the first dead-lock does prove ineffectual for any reason, the movement of said fastener, now induced by the action of the sash on said first dead-lock, forces the second dead-lock into engagement 85 with said sash, as shown in Fig. 4. When the dead-lock 7 is swung, by the action of the cam-lock 5, against the sash, it bites into said sash as the latter continues to be moved in the direction to open the window, and 90 successfully checks further movement in that direction on the part of said sash, unless the parts be very loose indeed or for some other reason the force exerted on the window is sufficient to overcome the resistance offered by said dead-lock. In nearly 95 all cases the dead-lock 7 holds and the window cannot possibly be forced farther in the direction to open it, because the distance between the pivotal point 11 or 13 and said 100 dead-lock is so much greater than the distance between said point and the nearest point on the sash, and the engagement between the fastener and sash is positive.

As hereinbefore intimated, the dead-lock 105 7 may fail to hold, such failure resulting from the splintering of the wood of the sash where it is engaged by said dead-lock, or from some other cause, in which event the fastener for the lower sash, provided it 110 be the lower sash and its fastener that are involved, is swung by said dead-lock, under the influence of continued force exerted upon the lower window to open it, so as to bring the dead-lock 9 into engagement with 115 said sash. The dead-lock 9, like the dead-lock 7, bites into the sash, and, owing to the construction and arrangement of this fastener, the more the force exerted to open the window the deeper said dead-lock 9 120 is driven into the wood, the action of the dead-lock 7 in engagement with said sash tending to this end. This locking of the lower window is not only positive but final, because the dead-lock 9, after once becoming engaged with the sash, will hold it, even in the event that an extraordinary force combined with an unusual condition 125 of the window members forces the sash away from the dead-lock 7, since said sash 130

cannot free itself from said dead-lock 9. That this is true will be readily seen upon noting the fact that in no case, without actually destroying some part of the window 5 members, can the tail-piece 8 be forced, by a window in the act of being opened, into a horizontal position, and without being forced into such position the sash of said window cannot free itself from said tail-piece. When the dead-lock 7 is in operative engagement with a sash, the head 4 is wedged in between the pivot and said sash; and when the dead-lock 9 is in such engagement with a sash, the tail-piece 8 is wedged 10 in between said pivot and said sash. Either deadlock is self-releasing upon the closing of the window, and the cam-lock 5 may be, but if said cam-lock is pressed too tightly against the sash by means of either 15 tail-piece, or by the action of the window, some assistance is sometimes required in order to loosen the fastener, such assistance being given by pressure applied to said tail-piece in the opposite direction to that necessary in the locking operation.

I am aware that window fasteners having cam-locks are old, and do not, therefore, lay claim to such a fastener *per se*.

More or less change in the shape, size, and

construction of this device may be made, 30 of course, without departing from the nature of my invention.

What I claim as my invention, and desire to secure by Letters Patent, is—

A window fastener having a pivotal 35 mounting point and two lock members, the first lock member consisting of a cam-shaped part having an engaging extremity, as 7, such engaging extremity being at the end of a reverse curve which continues from 40 the cam, and the second lock member consisting of a combined emergency dead lock and handle part projecting at an angle and having a sharp engaging point, as 9, said engaging point being a greater distance from 45 the pivotal point than the engaging extremity of the other member, the relation between the two lock members being such that the point 9 engages the frame before the point 7 is released from the frame, and said point 7 is the means whereby said point 50 9 is actuated into engagement with the frame.
